C. F. SHADLE

SWITCH ATTACHMENT FOR ENGINEERS' AUTOMATIC BRAKE VALVES

Filed Dec. 10, 1923

UNITED STATES PATENT OFFICE.

CLINTON F. SHADLE, OF INDIANAPOLIS, INDIANA, ASSIGNOR TO INDIANA EQUIPMENT CORPORATION, OF INDIANAPOLIS, INDIANA, A CORPORATION.

SWITCH ATTACHMENT FOR ENGINEERS' AUTOMATIC BRAKE VALVES.

Application filed December 10, 1923. Serial No. 679,750.

To all whom it may concern:

Be it known that I, CLINTON F. SHADLE, a citizen of the United States, and a resident of Indianapolis, county of Marion, and 5 State of Indiana, have invented a certain new and useful Switch Attachment for Engineers' Automatic Brake Valves; and I do hereby declare that the following is a full, clear, and exact description thereof, 10 reference being had to the accompanying drawings, in which like numerals refer to like parts.

This invention relates to a switch construction included in an automatic train 15 control system not described or claimed herein, but which forms the subject matter of a separate application, wherein permissive operation of a train provided with air brakes is permitted by the engineer or en- 20 gineer operating certain control switch means when the train control system is arranged for either the total or partial non-operation of the train.

The chief object of the invention is to in- 25 corporate such a switch means with the engineer's normal controlling means, to-wit, the engineer's brake valve, whereby there is obtained simultaneous and predetermined operation between the immediate electrical 30 circuits controlled by the switch construction and the braking system controlled by the engineer's valve.

The chief feature of the invention consists in the construction of the parts constituting the switch construction so that 35 they may be applied, to the standard H-6 engineer's automatic brake valve, as an attachment with a minimum amount of change to said valve and with a maximum 40 degree of accuracy and simplicity of construction, whereby the aforesaid predetermined and coordinated control is secured.

Other features of the invention consist in the details of construction embodied in the 45 switch means and the supporting parts associated therewith.

The full nature of the invention will be understood from the accompanying drawings and the following description and 50 claims:

In the drawings, Fig. 1 is a top plan view of an engineer's automatic brake valve, and

that herein illustrated is known in the art as the H-6 type. Fig. 2 is a side elevational view of so much of the same as is necessary 55 for an understanding of the invention. Fig. 3 is a top plan view of the switch construction the handle and the valve showing the association therebetween. Fig. 4 is a side elevational view of substantially the 60 same parts illustrated in Fig. 2 with the replacing handle and with the switch construction shown in section to illustrate other parts in detail. Fig. 5 is a top plan view of one of the switch elements. Fig. 6 is an 65 end elevational view of a portion of the switch support. Fig. 7 is a diagrammatic view of the switch and valve showing a pre-determined coordination between the electrical circuits and the pneumatic circuits. 70

In Figs. 1 and 2 of the drawings 10 indicates the flange upon the body of the engineer's automatic brake valve of the H-6 type. 11 indicates a complementary flange upon the valve head 12 which carries a 75 cap 13 and an operating shaft 14. The operating shaft 14 carries a lever or operating handle 15 suitably secured thereon by the locking nuts 16. The handle is offset as at 17 and supported thereby is a position 80 indicating pointer or projection and notch-engaging toothed construction 18 adapted to engage in the notches 19 formed in the collar 20 upon the neck 12. The valve head 12 also is provided with a projecting 85 tongue 21.

Reference will now be had particularly to Figs. 3, 4 and 6, wherein the connection between the switch construction and the engineer's automatic brake valve previously described and its mounting and support thereby is illustrated in detail. The handle 15 of Figs. 1 and 2 is replaced by a handle 115 substantially similar thereto having an offset portion 117 and carrying the projection 118 substantially identical with that previously described. However, extending oppositely from the handle portion and outwardly therefrom is a projection 23, which projection 23 is axially slotted as at 24. 100 Communicating with said axial slot 24 and extending toward the mounting of the handle is a recess 25 reduced in area. Said recess 25 is adapted to contain a coil spring

26, and the slot 24 is adapted to receive a tongue or tooth 27. The tongue or tooth 27 is apertured at 28, and said aperture is elongated. In alignment with said aperture 28 and in the projection 23 is a pair of transversely positioned and aligned openings adapted to receive the securing bolt 30. The securing bolt 30 thus permits the tooth 27 to have slight relative axial movement but prevents its removal from the slot receiving the same. The spring 26 maintains the tooth 27 in its outermost position in engagement with a complementary part hereinafter to be described. The foregoing 15 constitutes the sole change in the handle; and it has been found more economical to provide a new handle 115 and supply there- 20 to the old part 18 and the new parts previously described than it is to attach the new parts to said handle 15. Likewise the replacement of the old handle by the new handle assures positive operation by and attachment to the handle of the switch construction, since the projection 23 is integral, 25 and, therefore, always rigid with said handle.

The switch construction is arcuate in form and is concentric with the center of the operating shaft 14 of the engineer's 30 automatic brake valve, and said switch construction is operable by said handle through the medium of the actuating tooth 27.

Herein the means for supporting the arcuate switch construction is illustrated particularly in Figs. 4 and 6 and includes an arcuate base or flange 31 having a radial groove 32 therein. Extending upwardly from said base is a standard 33, and cooperating with said standard is a reinforcing web 34, said web and said standard thus forming a support for the arcuate switch construction, the details of which are hereinafter to be described. It will be observed from Fig. 4 that the base 31 is superposed with respect to the complementary flanges 10 and 11 and is simultaneously secured thereto with them by the customary bolt 35 and nut 36. For this purpose the flange 31 is provided with suitable bolt-receiving apertures. When thus positioned, the tongue 21 is received by the groove 32 which aligns the base with respect to the valve head 12. Since the head 12 carries the positioning collar construction 22, the entire switch construction will be aligned with respect to the valve and, therefore, operable in predetermined relation with said valve.

In Figs. 3 and 4 there is illustrated an arcuate laterally channeled frame having 60 the side 37, the top 38 and the bottom 39. Extending downwardly from said bottom 39, is a flange 40, and extending upwardly from said top 38 is a plurality of collars or bosses 41 each of which is recessed as at 42 to register with an opening 43 in the top 38.

The boss 41 is externally threaded to receive an internally threaded cap 44, which cap also contains an insulation disk 45. Mounted in the opening 43 is an insulated bushing 46; and upon each side of the top in alignment with said opening 43 there is positioned insulation washers 47. Rigidly secured in said insulated opening thus formed is a brush or contact guide 48 having a collar 49 adapted to bear upon one of the 75 washers 47. A locking nut 50 is associated with said contact guide and serves to rigidly mount the same in the insulated opening previously described. An adjusting screw 51 is associated with said guide 48 and serves to adjust the position of the brush 52 or contact carried by said guide 48. A suitable entrance for the circuit wire is provided, but herein is not illustrated.

Opposite the arcuate face 37 is an arcuate plate 53, which arcuate plate 53 is adapted to form with the framework previously described an arcuate housing. Said arcuate plate 53 is provided with three parallel projections 54, 55 and 56. The projections 54 and 55 are adapted to respectively overly and underly the top 38 and thus form a tongue and groove connection. The lateral projection 56 is adapted to overly the bottom 39 and form a base to which an arcuate insulation strip 57 is secured by suitable means such as the screws 58, and said insulation strip carries an arcuate conducting strip 59. The strip 59 is adapted to bridge the contacts 52 selectively and either open the circuits or selectively close one of two circuits, all in predetermined relation and in coordination with the positioning of the valve previously described. The plate 53 carries a pair of projections 60 which form a seat or slot 61, see Fig. 3, adapted to receive the tongue 27 carried by the valve. Thus rotational movement of the handle 115 causes, through the engagement of the tongue 27 with the projections 50, rotational movement of the plate 53 and the bridging contact 59 into and out of contact with the respective contacts 52. Herein three of such contacts are illustrated to form two circuits; the central contact acting as a common line for the two outside contacts. As shown in Fig. 7, the switch is arranged to maintain both circuits in open position or either circuit in closed position.

While the invention has been described in great detail in the foregoing specifications, the same is not to be understood as restrictive in character. As pointed out in the forepart of the specification, the invention consists in the broad idea of mounting a switch construction upon a controlling member, so that the switch and the means controlled by the controlling member will be operated simultaneously and in predetermined relation, and also that said switch may be at-

tached to the controlling member with a minimum of effort and change in the controlling member.

In addition to the foregoing, the arrangement and construction of the switch is also a part of this invention. All of the modifications which will readily suggest themselves to those skilled in the art to which this invention applies are considered to be 10 within the broad purview of this invention, as outlined by the appended claims.

The invention claimed is:

1. The combination with an engineer's 15 brake valve for an air brake system having a handle, of a replacing handle similar thereto and including a projection, switch means detachably but rigidly supported upon said valve adjacent the handle and operable by said projection.

2. The combination with an engineer's 20 brake valve for an air brake system having a rotatably movable portion for control purposes, and a flange, of a switch construction including a base adapted to be rigidly secured to said valve flange, and a connection 25 between said switch construction and said valve control portion for operating said switch simultaneously with said valve.

3. The combination with an engineer's 30 brake valve for an air brake system having a rotatably movable portion for control purposes, and a flange, of a switch construction including a base adapted to be rigidly secured to said valve flange, and a connection between 35 said switch construction and said valve control portion for operating said switch simultaneously with said valve, and in predetermined relation between the circuit means controlled by the switch and the air brake 40 means controlled by the valve.

4. The combination with an engineer's 45 brake valve for an air brake system having a handle including a projecting portion, of a switch construction including a base adapted to be rigidly secured to said valve flange, and means associated with said switch construction engageable by said handle projection for actuating said switch construction when said valve is actuated.

5. The combination with an engineer's 50 brake valve for an air brake system having a handle including a projecting portion, of a switch construction including a base adapted to be rigidly secured to said valve flange, and means associated with said switch construction engageable by said handle projection for actuating said switch construction when said valve is actuated, and in predetermined relation between the circuit means 55 controlled by the switch and the air brake means controlled by the valve.

6. The combination with an engineer's 60 brake valve for an air brake system having a rotatably movable portion for control purposes, and an arcuate flange including a

radial tongue, of a switch construction including an arcuate base having a radial groove therein adapted to receive the radial tongue and adapted to be rigidly secured to said valve flange, and a connection between 70 said switch construction and said valve control portion for operating said switch simultaneously with said valve.

7. The combination with an engineer's 75 brake valve for an air brake system having a handle including a projecting portion, of a switch construction including an arcuate base having a radial groove therein adapted to receive the radial tongue and adapted to be rigidly secured to said valve flange, and means associated with said switch construction engageable by said handle projection for actuating said switch construction when said valve is actuated.

8. The combination with an engineer's 80 85 brake valve for an air brake system having a rotatably movable portion for control purposes, and an arcuate flange including a radial tongue, of a switch construction including an arcuate base having a radial 90 groove therein adapted to receive the radial tongue and adapted to be rigidly secured to said valve flange, and a connection between said switch construction and said valve control portion for operating said switch simultaneously with said valve, and in predetermined 95 relation between the circuit means controlled by the switch and the air brake means controlled by the valve.

9. The combination with an engineer's 100 brake valve for an air brake system having a handle including a projecting portion, of a switch construction including an arcuate base having a radial groove therein adapted to receive the radial tongue and adapted to be rigidly secured to said valve flange, and means associated with said switch construction engageable by said handle projection for actuating said switch construction when said valve is actuated, and in predetermined 105 relation between the circuit means controlled by the switch and the air brake means controlled by the valve.

10. In a switch construction, the combination of an arcuate laterally channeled frame, 110 a plurality of contacts supported thereby, an arcuate plate arcuately movable relative to the frame, and contact bridging means carried by said plate.

11. In a switch construction, the combination of an arcuate laterally channeled frame, a plurality of contacts supported thereby, an arcuate plate arcuately movable relative to the frame and having an arcuate tongue and groove connection with said frame, and contact bridging means carried by said plate.

12. In a switch construction, the combination of an arcuate laterally channeled frame, a plurality of contacts, individual means ad- 130

justably supporting each of said contacts upon said frame, an arcuate plate arcuately movable relative to the frame, and contact bridging means carried by said plate.

5. 13. In a switch construction, the combination of an arcuate laterally channeled frame including a plurality of bosses in arcuate arrangement, a similar number of contacts,

means associated with and enclosed by said bosses for adjustably supporting said contacts upon said frame, an arcuate plate arcuately movable relative to the frame, and contact bridging means carried by said plate.

In witness whereof, I have hereunto affixed my signature.

CLINTON F. SHADLE.
